UNITED STATES PATENT OFFICE.

THEODORE HOOK, OF COLOGNE, BAYENTHAL, GERMANY, ASSIGNOR TO WESTINGHOUSE ELECTRIC AND MANUFACTURING COMPANY, A CORPORATION OF PENNSYLVANIA.

ELECTRICALLY-HEATED APPARATUS.

1,146,328.

Specification of Letters Patent. Patented July 13, 1915.

Application filed October 23, 1912. Serial No. 727,293.

To all whom it may concern:

Be it known that I, THEODORE HOOK, a subject of the Emperor of Germany, and a resident of Cologne, Bayenthal, Germany, 5 have invented a new and useful Improvement in Electrically-Heated Apparatus, of which the following is a specification.

My invention relates to electrically heated apparatus, and it has particular reference 10 to cooking devices such as ranges and stoves of the so-called "heat-storage" type, in which electrical energy is supplied continuously at a low rate and the heat thereby produced, is accumulated or stored and may be 15 utilized for heating or cooking operations at any rate that may be required.

The object of my invention is to provide a device of the above indicated character, that shall be simple and durable in construction, 20 efficient in operation and that shall embody a variety of structural features which contribute to the utility and safety of the device, as a whole, and render the same conveniently adaptable for various cooking operations.

In the accompanying drawings, Figure 1 is a view, partially in front elevation and partially in section, of a device constructed in accordance with my invention. Fig. 2 is 30 a view, partially in side elevation and partially in section, of the device shown in Fig. 1. Fig. 3 is a view, in side elevation, of the frame structure upon which the heating device is constructed. Fig. 4 is a view, in side 35 elevation, of a modified form of my invention. Fig. 5 is a plan view, partially in section, taken along the lines V—V of Fig. 4, and Fig. 6 is an enlarged view, partially in side elevation and partially in section, of a 40 portion of the device shown in Fig. 1.

Referring to Figs. 1, 2, 3 and 6, the apparatus shown comprises a frame structure 1, a heat-storage body 2, an electric heater 3, heat-insulating walls 4, removable pads 5 and 6, a thermally-controlled protective device 7, a shelf 8, supporting brackets 9, 10 and 11, a movable bottom member 12, a movable oven 13, and a power-actuated linkage mechanism 14. The frame structure 1 of the range is preferably constructed of a plurality of angle irons 17 which may be assembled in substantially the manner shown in Fig. 3, and be adapted to support the heat-storage body 2 in a suitable man-

ner. The storage body 2 comprises a main 55 body portion 18, having integral upwardly projecting members 19, the upper surfaces 20 of which are flush with the angle irons or cross pieces 17^a. The storage body 2 may conveniently be made of cast iron or 60 other material suitable for storing up and accumulating heat that may be imparted thereto at a slow rate, and said body 2 is provided with the electric heater 3 which is secured to the bottom thereof. Since the 65 heater unit 3 forms no part of my present invention, except as it performs a necessary function in the operation of the device, it may be of any suitable construction. A terminal box 23 is provided, and leads 24 from 70 the heater unit 3 terminate therein for the purpose of connection with an external source of energy. The walls 4 of suitable heat-insulating material, are disposed between the heat-storage body 2 and the frame 75 structure 1 and serve to prevent the loss of heat by radiation. Disposed upon the angle irons 17^a of the frame structure 1, are the removable pads 5 of heat-insulating material and said pads are thus adapted to cover the 80 upper surfaces 20 of the projecting members 19, which I shall hereinafter term "hot-plates". The pads 5 are slidably disposed with relation to the angle irons 17^a of the supporting structure 1 in order that they 85 may be withdrawn, by means of handles 26, to expose the upper surfaces 20 of the hot-plates 19 for cooking purposes. Side brackets 27 are provided to support the pads 5 when they occupy their outer positions, as 90 shown in Fig. 1. Under normal conditions, when the range is not being used for cooking purposes, the pads 5 cover the hot-plates 19 and prevent the radiation and loss of heat from the storage body 2. Obviously, 95 the pads 5 may be withdrawn to expose one or more hot-plates 19, as desired, and, when withdrawn, the upper surface of the range is smooth and unbroken and is free from any depressions or holes in which dirt and food 100 may collect. Thus the cooking surface may be readily cleaned and maintained in sanitary condition. The removable pad 6 is located directly below the heat-storage body 2 and is provided with a handle 26^a by 105 means of which it may be withdrawn to provide an opening (not shown) which is exposed to the heat-storage body 2 as will

be readily understood. Brackets 27^a are also provided to support the pad 6 in its outer position. Furthermore, a door 28 is provided in the front wall of the range to cover the opening referred to, when the removable pad 6 is withdrawn. By reason of this construction, a portion of the bottom of the heat-storage body 2 is exposed and may be utilized to supply heat to meats or other materials for broiling or similar purposes, it being understood that a pan or other receptacle (not shown) may be disposed in the opening beneath the material to be cooked, for the purpose of collecting the juices, etc.

In order to prevent the possibility of sufficient heat accumulating in the heat-storage body 2 to raise the same to a dangerously high temperature, I employ the thermally-controlled protective device 7 which is located within a passage 30 that is disposed in proximity to a portion of the heat-storage body 2 and is provided with a plurality of exterior openings 31 and 32, one above the other, said openings being provided with screens 33. The device 7 comprises a damper 34 that is pivotally mounted upon a pin 35, and, in its closed position, rests against flanges 36. A pin 37 projects from the damper 34 and cooperates with the bifurcated end 38 of a rod 39 which is surrounded by a spring 40, the respective ends of which are associated with the rod 39 and the damper 34. The other end 41 of the rod 39 is secured to the free end 42 of a bi-metal thermostat 43 which is associated with the heat-storage body 2 and is of well known construction.

The structural details of the protective device 7 just set forth, are not material to my present invention, since any other suitable device for thermally controlling the operation of the damper 34 may be employed.

Assuming the various parts of the device 7 to occupy the positions shown, and that the temperature of the heat-storage body 2 is raised above a predetermined value for which the thermostat 43 is adapted, the operation of the device is as follows: By reason of the peculiar construction of the thermostat 43, the free end 41 thereof is moved outwardly when the temperature exceeds the predetermined value, and, in so doing, the damper 34 is opened through the agency of the rod 39 and the pin 37, as will be readily understood. Thus, the heat which has accumulated in the upper portion of the passageway 30 is allowed to escape, by means of the circulation of air which is established through the passage 30 and in proximity to the heat storage body 2, whereby the excessive heat thereof is carried away and the temperature is accordingly reduced. As the temperature of the heat-storage body 2 is lowered, the free end 41 of the thermostat

43 tends to assume its original position, whereby the damper 34 is again closed by reason of its connection with the spring 40.

The shelf 8 is disposed above the range hereinbefore described, and is rigidly supported by means of the side brackets 9 and 10 and the rear bracket 11, said supporting brackets 9, 10 and 11 being amply provided with heat-insulating material for the purpose of preventing radiation of heat under certain conditions that will be hereinafter set forth. The shelf 8 is provided with an opening 40^a which is covered by the movable bottom member 12 that is pivotally mounted upon a rod 41^a and is normally maintained in its closed position as shown in Figs. 1 and 2, by means of a spring 42^a that surrounds the rod 41^a. The movable bottom 12 is also provided with heat-insulating material and, when the rear pads 5 are withdrawn, said member 12 may be swung downwardly into the position shown in dotted lines in Fig. 2, thereby providing a confined heat-insulated passage which communicates between the exposed rear hot-plates 19 of the heat-storage body 2 and the oven 13 which normally rests upon the shelf 8. A spring-actuated button 44 is provided in the side bracket 9 to coöperate with a suitable recess 45 in the bottom member 12, whereby said member may be held in its lowered position against the action of the spring 42^a. A handle 46 is rigidly connected to the rod 41^a for the purpose of turning the movable bottom member 12 to its lower position.

The oven 13 is open at the bottom and normally rests upon the shelf 8 directly over the opening 40^a therein, and the power-actuated linkage mechanisms 14 are associated with said oven in such manner as to tend to raise the same to its upper position, as shown in dot and dash lines in Fig. 2. The actuating mechanisms 14 are of the well-known pantograph construction and are severally disposed at the respective ends of the oven 13 and are adapted to operate concurrently. Each of the pantograph linkages 14 comprises a plurality of sets of arms 48 and 49 which are pivotally connected. The upper ends of the arms 48 are pivotally associated with the oven 13 by means of pins 51 while the lower ends of the arms 49 are respectively fixed to shafts 52 upon which segments 53 are also rigidly mounted. A heavy coil spring 54 is disposed between the segments 53 and the respective ends thereof are secured thereto. The contour of the segments 53 is so designed that the turning moment about the shafts 52, due to the spring 54, shall always be of sufficient value to raise the oven 13 to its upper position, regardless of the intermediate position that the oven may occupy. Although I find the pantograph mechanism, hereinbefore set forth, to be particularly adaptable

for the purpose intended, I do not wish to be confined to this specific mechanism, as any other suitable means for raising the oven 13 may be employed.

5 Inasmuch as the operating mechanisms 14 always tend to raise the oven 13 to its upper position, it is necessary to provide means for restraining the same in its lower position upon the shelf 8. I, therefore, provide 10 a locking means 55 that comprises members 56 which project downwardly from the bottom edge of the oven 13 and are adapted to be engaged by suitable detents or latches 57 that are associated with a rod 58 that is 15 located in the middle of the shelf 8 and projects therethrough. The rod 58 is provided with a handle 59 and is normally adapted to effect the engagement of the detents 57 with the members 56 by reason of a spring 20 60. A rack 62 or other device for supporting the materials to be cooked in the oven 13 is provided and is adapted to rest upon the shelf 8 when the oven 13 occupies its lower position.

25 Assuming the various parts of the device to occupy the positions shown in Figs. 1 and 2 and the bottom member 12 to be in its lower position as shown in dotted lines in Fig. 2, it is evident that heat is supplied 30 from the exposed rear hot plates 19 of the heat-storage body 2 through the confined passage, hereinbefore described, and opening 40^a to the oven 13. When sufficient heat has thus been supplied to the oven 13, the 35 bottom member 12 may be raised to its upper position, thereby covering the bottom opening 40^a in the shelf 8 after which the rear pads 5 may be pushed in to cover the hot-plates 19. Thus, the heat of the 40 heat-storage body 2 is conserved and the oven 13 may be employed as a so-called "fireless cooker," in accordance with well-known principles. In this way, the cooking operation continues in the oven 13 without 45 further utilization of heat, while the heat continuously delivered to the heat-storage body 2 accumulates therein, for future use. If, at any time, it is found that the cooking operation is proceeding too slowly, 50 additional heat may be supplied to the oven 13 by withdrawing the rear pads 5 and lowering the bottom 12 as hereinbefore set forth. Obviously, if rapid cooking be desired, heat may be supplied to the oven 55 continuously in the usual manner. When the cooking operation is completed, the oven 13 may be raised into its upper position shown in Fig. 2 merely by releasing the locking means 55 by means of the handle 59. Upon 60 the release of the latches 57, the pantograph linkage mechanism 14 raise the oven as hereinbefore set forth, leaving the rack 62 and cooked materials thereon, readily accessible. In order to lower the oven 13 to 65 its normal position, it is only necessary to

employ a handle 63 and to pull the oven down in opposition to the action of the operating mechanisms 14.

Reference may now be had to Figs. 4 and 5 which illustrate a range of similar type to 70 that already described and having an oven 13 provided with operating mechanisms 14 and other devices like those hereinbefore set forth. The oven 13 is adapted to normally rest directly upon the cooking surface 20 75 when the rear pads 5 are removed. In place of the shelf 8 and the removable bottom member 12, this modified form of my invention is provided with a bottom member 12^a that is pivotally mounted at the rear and 80 lower edge of the oven 13 in such manner that, when the oven is in its lowered position, the bottom member 12^a hangs downwardly at the back of the main body of the range, as shown in Fig. 4. Furthermore, 85 in order that the rack 62 may be rigidly associated with the oven 13, I provide a locking means 66 that is somewhat similar in construction to the locking means 55 for restraining the oven 13 in its lowered position. 90 This locking means 66 is located near the top of the oven 13 and embodies rods 58^a which are connected and provided with a handle 59^a. Latches or detents 57^a are associated with said rods 58^a for the purpose 95 of engaging members 56^a that are associated with the rack 62. A latch 68 is also provided to restrain the bottom member 12^a in its upper or closed position.

Assuming the apparatus to occupy the positions shown in Fig. 4, when sufficient heat has been imparted to the oven 13, the locking means 55 is released, thereby allowing the operating mechanisms 14 to raise the oven 13 and associated rack 62 to its upper 100 position, as shown in dotted lines. The bottom member 12^a is then swung into its upper position and retained therein by means of the latch 68, thereby completely closing the oven 13 which may be employed as a "fireless cooker" in the same manner as hereinbefore set forth. When the cooking operation is completed, the bottom member 12^a is lowered and the oven 13 together with 105 rack 62, is pulled down to its normal position by means of the handle 63, after which the locking means 66 and latch 68 may be released and the oven 13 again raised in order to permit access to the materials upon the rack 62, which thus remains in its 110 lowered position. When the materials have been removed, the oven 13 may be lowered and the rack 62 locked to the oven by means of the locking device 66, after which the oven 13 and the rack 62 may be again raised 115 to their upper positions where they interfere, in no way, with further operations upon the range.

Obviously, various modifications may be effected in the structural details and in the

arrangement and location of parts without departing from the spirit and scope of my invention, and I intend that such modifications shall be covered in the appended claims.

5 I claim as my invention:

1. A heating device comprising a supporting structure, heat-insulating walls therefor, a heat-storage body disposed within said walls and having members integral with said body projecting upwardly through the upper wall, electrical means for delivering heat to said body, and removable members or pads of heat-insulating material covering the upper faces of said projecting members.
- 10 2. A heating device comprising a supporting structure, heat-insulating walls therefor, a heat-storage body disposed therein, means for electrically heating said body, one of said walls having a heating chamber communicating with the bottom of said body, a heat-insulating cover or door for said chamber and a cooking space communicating with the top of said body.
- 15 3. A heating device comprising a supporting structure, heat-insulating walls therefor, a heat-storage body disposed therein, means for electrically heating said body, a removable pad of heat-insulating material disposed immediately below said body, and a door for covering the opening provided when said pad is partially withdrawn.
- 20 4. In a heating device, the combination with a supporting structure, heat-insulating walls therefor, a heat-storage body disposed within said walls and means for electrically heating said body, of automatically operating means for effecting a circulation of cooling air in proximity to a portion of said body under predetermined conditions.
- 25 5. In a heating device, the combination with a supporting structure, heat-insulating walls therefor, a heat-storage body disposed therein and electrical means for heating said body, one of said walls having a passage disposed in proximity to a portion of said body and having a plurality of openings, of means normally tending to close said passage, and automatic means for opening said closing means under predetermined conditions.
- 30 6. In a heating device, the combination with a supporting structure, heat-insulating walls therefor, a heat-storage body disposed therein and means for electrically heating said body, one of said walls having a passage disposed in proximity to a portion of said body and having a plurality of exterior openings, of a damper in said passage, and thermal means for actuating said damper under predetermined heat conditions.
- 35 7. In a cooking device, the combination with a range embodying a heat-storage body, an electric heater therefor and heat-insulating walls and removable pads enveloping said body, of an oven having a bottom opening

adapted to communicate with said heat-storage body when said pads are removed, and means for elevating said oven above said rings.

8. In a cooking device, the combination with a range embodying a heat-storage body, means for heating said body, and heat-insulating walls and removable pads for preventing the radiation of heat therefrom, of an oven having a bottom opening adapted to communicate with said heat-storage body when said pads are removed, and a power actuated linkage mechanism for raising said oven above said range.

9. In a cooking device, the combination with a range embodying means for electrically heating the same, of an oven supported above said range, and means for providing a confined passage between said range and said oven.

10. In a cooking device, the combination with a range embodying means for electrically heating the same, of a separate movable oven for said range having a removable bottom, and means for elevating said oven above said range.

11. In a cooking device, the combination with a range embodying a heat-storage body, an electrical heater therefor, and heat-insulating walls and removable pads enveloping said body, of an oven disposed above said range, means for supporting the same, and a pivotally mounted member constituting the bottom of said oven and adapted to be swung downwardly to form a confined passage between said storage body and said oven when said pads are removed.

12. In a cooking device, the combination with a range embodying a heat-storage body, an electric heater therefor, and heat-insulating walls and removable pads enveloping said body, of an oven disposed above said range and having a bottom opening, and means for providing a confined passage between said storage body and said oven when said pads are removed.

13. In a cooking device, the combination with a range embodying a storage body, an electric heater therefor, and heat-insulating walls and removable pads for enveloping the same, of an oven disposed above said range and having a removable bottom, and means including said removable bottom and pads for providing a confined passage between said storage body and said oven.

14. In a cooking device, the combination with a supporting structure, a heat-storage body disposed therein, electrical means for heating said body, removable heat-insulating pads for covering a portion of the upper surface of said body, and heat-insulating walls enveloping the remainder of said body, of a supporting bracket disposed above said supporting structure and having a bottom opening, a heat-insulating oven having a

bottom opening disposed upon said supporting bracket and over said bracket opening; and a pivotally mounted cover of heat-insulating material for said bracket opening and adapted to be swung downwardly to provide a confined passage from the heat-storage body to said oven when a portion of said pads are removed.

15. In a cooking device, the combination 10 with a range and means for electrically heating the same, of an oven having a bottom opening and adapted to rest upon said range, a rack disposed within said oven, means for securing said rack to said oven 15 and mechanical means for raising said oven above said range.

16. In a cooking device, the combination 20 with a range and means for electrically heating the same, of an oven having a removable bottom and adapted to rest upon said range, mechanical means normally tending to raise said oven above said range, and means for latching said oven in its lowered position.

17. In a heating device, the combination 25 with a supporting structure, heat-insulating walls therefor, a heat-storage body disposed therein and means for heating said body, of a heat-insulating pad slideable outwardly and laterally to expose a heating surface of said body. 30

18. In a heating device, the combination with a heat-storage body, and an electric heater and heat-insulating walls therefor, of a heat-insulating pad normally covering a heating surface of said body and slideable 35 outwardly and laterally to expose said heating surface, and means for supporting said pad in its outer position.

In testimony whereof, I have hereunto subscribed my name this 5th day of Aug., 40 1912.

THEODORE HOOCK.
